ABSTRACT OF THE DISCLOSURE

A tiltable door mounted in a door frame for swinging movement overhead comprises rotatably mounted drivable rollers adjacent the upper edge of the door. The rollers are engaged in horizontally extending stationary guide rails, and a compensating arm is provided on each side of the door and pivotally connected to the door frame portions adjacent the respective sides of the door. One end of each compensating arm is hingedly connected adjacent the lower edge of the door. The effective length of the lever arm of each compensating arm can be varied between its hinged connection to the door and is pivotal connection to the door frame. The ends of each compensating arm adjacent the door are mounted on a two armed intermediate lever. One arm of the intermediate lever is connected to the door and the other arm is engaged by an adjustable spring connected to the compensating arm.

This invention concerns improvements in or relating to doors such as garage doors of the type which can be swung overhead, which are guided by means of preferably drivable rollers which are rotatably mounted thereon in the region of the upper edge of the door and run in substantially horizontally arranged, stationary rails and to which doors in the region of the lower edge are hingedly connected one end of each of two compensating arms, which are pivotably mounted on the opposite longitudinal members of the door frame, the other ends of these compensating arms each being connected to a tension spring secured to the door frame.

For moving a door, particularly a garage door numerous operating means are known, some of which are based on the principle of providing a weight compensation so as to move the door panel more easily. For this purpose a shaft, engaged by and acted on by at least one torsion spring, is provided, each end of which shaft carries a cable drum, by means of which drums cables each of which engage one end of the side surfaces of the door panel, can be wound when the door is opened. The door panel of such doors consists preferably of several, hingedly interconnected parts which are so guided by rollers mounted thereon in rails that in the open position the door panel extends substantially in the horizontal plane. For constructions of doors which are substantially rigid operating mechanisms are known, which comprise an operating shaft which is mounted on the upper end of the door panel and can be rotated, for example, by an electromotive driving mechanism, each end of this shaft carrying a roller guided in upper horizontal guide rails. By rotation of the operating shaft, the rollers are then rotated and since at least their outer surfaces are made of a material which makes good frictional contact with the material of the guide rails, the opening of the door is effected by the rollers "pushing" along the guide rails and thus urging the door panel into the open position. In such operating mechanisms a weight compensation is also provided by means of spring-loaded compensating arms.

2

The present invention takes as its starting point preferably operating mechanisms of the type last mentioned above, in which particularly the phenomenon has to be taken into account that during the initial opening movement of the door panel the rollers move in a curved path in the substantially horizontally disposed stationary rails. If care is not taken to ensure that during this initial stage the rollers remain in frictional contact with these guide rails, difficulties occur when opening the door, in which connection it should be taken into account that, as a rule, compared to the diameter of the rollers, the guide rails have a larger open cross section in order to facilitate this initial curved movement of the rollers and to prevent the guide rails being torn from their anchorage. The statements made here on the initial stage of opening a door obviously also apply to the end stage of the closing action, i.e. when the door has been moved back from its open position into its closed position.

In order to deal with the above-mentioned problem it has already been proposed for doors of the abovementioned kind to mount the ends of the guide rails which are adjacent the door frame so that they will be adjustable in height and to bias them by means of a spring in such a way that the rails can carry out movements in height and their contact surfaces are continuously kept in frictional contact with the rollers. Hence when the movement of the door necessitates a deviation during the initial stage of opening or during the final stage of closing, this is effected against the resistance of such springs, and these will then cause the rollers to be kept in continuous frictional contact with their rails. According to a further proposal for dealing with this problem, the rollers are mounted in spring-loaded bearings which are movable as regards their spacing from the door panel so that frictional contact can be maintained by means of corresponding movements of the rollers.

Particularly when taking into account the point of view that it is often desirable to convert doors originally arranged for manual operation into automatically opening and closing doors by associating a suitable operating device therewith, it is an object of the invention to provide for a door of the above-mentioned type, which can be swung overhead, a device which, even in a manually operated door subsequently converted into an automatically opening and closing door by associating an operating mechanism therewith, controls without considerable building costs the problem arising from the fact that in the initial stage of opening and in the final stage of closing, the rollers follow a curved path and that as a result the frictional contact between the rollers and the substantially horizontally arranged, stationary guide rails may be lost. The device according to the invention should thus likewise ensure a continuous frictional contact between the rollers and their guide rails.

This object is achieved in a door of the above-mentioned type, which may be swung overhead, and according to the invention in that the effective lever arm of each compensating arm, between the hinge point of the compensating arm on the door and its pivotal axis on the door frame is variable in length. If use is made of this condition this has the consequence that during any desired phase of the opening or closing the rollers rest with a certain component of the weight of the door panel on the guide rails. Consequently the frictional contact between the rollers and their guide rails adjusts itself automatically during the working cycle of opening and closing. The size of the weight of the door panel will be automatically taken into account in this manner. If the weight of the door is high, the weight load on the rollers is high and the frictional contact between the rollers and their guide rails will then be correspondingly large. On the other hand, with a door of low weight, the weight component acting

on the rollers is correspondingly less as is the frictional contact between the rollers and their guide rails.

The variation of the effective lever arm of each compensating arm between its hinge point on the door and its pivotal axis on the door frame can be carried out in any desired manner. Firstly it is possible to provide the compensating arms at their ends near the door panel with an elongate slot for the hinge pin fixed to the door panel; additionally also preferably adjustable springs can be provided which tend to urge the hinge pins in the direction of the end of the elongate slot adjacent the end of the compensating arm. Dependent on the magnitude of adjustment of their spring force, such springs can influence the magnitude of the force which can be transmitted by frictional contact, that is the weight of the door panel. It is furthermore possible to hingedly connect the door panel ends of the compensating arms to points along the length of two-armed intermediate arms, one end of which is pivotably mounted on the door panel, and the other end of which is connected to a preferably adjustable spring which acts in the vertical direction and is connected to a point along the compensating arm. It is also possible to provide in the region of the pivotal axis of the compensating arms on the door frame an elongate slot for the hinge pins supporting the compensating arms on the frame.

A variation in length of the effective lever arm between the hinge of the compensating arms on the door and their pivotal axis on the door frame is also made possible in that the compensating arms in the region between their hinge point on the door and their pivotal axis on the door frame are made from two parts which are guided so as to be movable with respect to each other to a limited extent. It can thus be advantageous to provide adjacent ends of the two parts with a projection or the like which passes through the opening of a sleeve or the like enveloping these parts. As seen in the direction of movement of the parts, the opening must then have a length which is greater than the thickness of the two projections or the like.

The above-mentioned possibilities show that the invention can be put into practice in a number of ways. A particularly simple and very elegant embodiment resides in replacing one of the hinge pins for mounting the compensating arms on the door or door frame in existing doors by a new hinge pin of smaller diameter, whilst also increasing the bore with which this cooperates to a greater or less extent.

The invention will now be described in more detail with reference to some embodiments by way of example shown in the accompanying drawings in which:

FIG. 1 is a side view, partially in section, of a tilting door of a garage, incorporating the invention,

FIG. 2 shows, to a larger scale, a detail of the door according to FIG. 1 with one embodiment according to the invention for changing the length of the effective lever arm between the hinge point on the door and its pivotal axis on the door frame,

FIG. 3 shows to a larger scale a detail of the door according to FIG. 1, showing a further embodiment according to the invention,

FIG. 4 shows to a larger scale a third possible embodiment,

FIGS. 5 and 6 show selectively usable operating means for a locking bolt fixed to the door,

FIG. 7 is a side view corresponding to FIG. 1 of a door according to the invention, showing a further embodiment of the device according to the invention,

FIG. 8 shows to a larger scale a detail of the embodiment according to FIG. 7, and

FIG. 9 is a side view of the detail according to FIG. 8.

The door which can be swung overhead, shown in FIGS. 1 and 7, comprises a door frame 1 to be fixed to the brickwork or the like, on which a door panel is supported and guided in the manner usual in tilting doors for garages or halls. Substantially horizontally arranged, stationary rails 3 which are supported under the garage ceiling

5 and are in most cases rigidly connected to the door frame 1, serve to guide the door panel. In these rails 3, rollers 4 are guided which are rotatably mounted on the door panel in the region of its upper edge and which are operatively connected with a driving motor 5 fixed on the door panel. When the rollers 4 are rotated by the motor 5, the door panel 2 is thus pulled into its open position or pushed into its closed position.

In the region of the lower edge of the door panel 2, 10 one end of two compensating arms 6 is hingedly connected at 7, by means of a hinge pin which can be mounted in a bracket 8. At the other end these compensating arms 6 are pivotably mounted at 9 to opposed longitudinal members of the door frame 1, also 9 being a hinge pin 15 which is mounted in a bracket 10. The free end of the compensating arms 6 is engaged by a tension spring 11 at 12, the other end of which is secured at 13 to an angle plate 14 which is rigidly connected to the door frame 1.

20 The door which can be swung overhead, and which consists of a door frame and a door panel, of preferably drivable rollers which are guided in stationary rails and are rotatably mounted opposite the upper edge of the door panel, and of spring-loaded compensating arms 25 which are arranged on the sides of the door panel and mounted on the door panel on one side and on the door frame on the other side, can be assumed to be known as far as described up to now. The present invention will now be described in more detail, particularly with 30 reference to FIGS. 2 to 4 and 8 and 9.

It is important for doors of the type described above, which can be swung overhead, that the rollers 4 are continuously kept in frictional contact with their guide rails 3. If this frictional contact is not maintained, the rollers are not able to pull the door panel 2 into its open position or correspondingly to urge it into its closed position. During the initial phase of opening and during the end phase of closing, the phenomenon now arises that the rollers try to detach themselves from the surface of their guide rail the width of opening of which is greater than the diameter of the rollers which seek to travel through a curved path. If, however, the rollers are detached for even only a moment from the surface of their guide rails, the necessary frictional contact ceases so that the rollers will idle. In order to avoid such an idling or slipping, it is now proposed by the present invention to change the 40 effective length of the lever arm of each compensating arm, between the hinge 7 of the compensating arms 6 on the door panel 2 and the bearing 9 of the compensating arms 45 on the door frame 1. This can be brought about especially on existing doors in a most simple manner in that the bearing hole in the supporting member 8 for the hinge pin 7 or the bearing hole in the bracket 10 for the hinge pin 9 is enlarged or, however and if desired, additionally the hinge pins 7 and 9 used are replaced by new pins of smaller diameters, in which case 50 however it must first be ascertained whether hinge pins of smaller diameter still have sufficient strength.

In the embodiment according to FIG. 2, a variation 55 of the length of the effective lever arms of the compensating arms 6 is brought in that their end adjacent the door panel are provided with an elongated slot 15 through which the hinge pin 7 passes. This elongated slot 15 ensures that in the closed position of the door panel 2, the rollers 4 thereof lie flush on the contact surface of their guide rails because the weight of the door panel 2 then rests on the rollers. If by rotating the rollers the door panel is pulled into its open position, the tension 60 springs 11 of the compensating arms 6 effect a shortening of the effective lever arm of the compensating arms between their hinge pins 7 and 9 in that the compensating arms are displaced relative to the hinge pins 7. Furthermore, in FIG. 2, an adjustable helical spring is designated by 16 which in its arrangement relative to the 65 compensating arms fulfills the function of either "increas-

ing" or "decreasing" in the closed position of the door panel, its weight and thus the weight resting on the wheels 4, i.e. always dependent upon the characteristic which has been chosen for this compression spring. In the embodiment shown, for example, the lower of the two spring discs on the side of the end face of the spring is secured relative to the compensating arm 6 and a set screw is supported between an angle plate and the pin 7 so that a stop is provided for the closed door panel. When the door is open, the compression spring 16 tends to bring about the relative movement between compensating arm 6 and hinge pin 7, i.e. to such an extent that the rollers 4 remain in continuous frictional contact with the surfaces of their guide rails.

In the embodiment according to FIG. 3 there is mounted on the hinge pin 7 at the door panel end of the compensating arm 6 an intermediate lever 17 which for its part carries via a hinge pin 18 the door panel end of a compensating arm 6. The free end of this intermediate lever 17 is acted upon by a preferably adjustable spring 19, the other end of which is fixed on the compensating arm. Also this embodiment makes it possible to change the length of the effective lever arm of the compensating arms.

In the embodiment according to FIG. 4, the bracket 10 is provided with an elongated hole 12, over the length of which the pin 9 of a compensating arm 6 can be moved. The door panel end of the compensating arms is mounted in this embodiment without play on the door panel 2 and the bracket 8 fixed thereon.

In the embodiments according to FIGS. 7 to 9, there are provided for each of the compensating arms 6 in the region of their pins 7 and 9 two parts 21 and 22 which are guided through a sleeve 23 or the like of a shape corresponding to the cross section of the compensating arms. The sleeve 23 can be rigidly connected to the part 21; it is only important that the part 21 carries the sleeve 23 when the door panel 2 is in its closed position.

In this position the parts 21 and 22, or the projections 24 and 25 formed thereon must engage one another so that the door panel provided with a bolt 26 (see FIG. 1) engaging behind a stop, cannot be opened by raising it. Nevertheless the part 22 must be able to move downwardly relative to the sleeve 23 in order to ensure that the rollers 4 have a continuous frictional contact with their guide rails.

As regards the bolt 26 which is mounted on the inside of the door panel 2 and the height of which is adjustable, it should further be noted with reference to FIGS. 5 and 6 that an automatic release of this bolt can be achieved, for example, in that the shaft carrying the rollers 4 is provided with a friction clutch and this is again connected via a cable or Bowden wire 28 to the bolt 26.

FIGS. 5 and 6 show two embodiments of such a friction clutch. As seen in FIG. 5 the clutch can consist of two friction discs 29 one of which is rigidly connected to the driven shaft 30 whilst the other is rotatably mounted on this shaft. The rotatably mounted friction disc is pressed by means of a spring against the driven disc and carries a connector or anchorage for the cable or Bowden wire 28. In the embodiment of friction clutch according to FIG. 6, the shaft 30 is formed by two friction bushings 31 which together surround the shaft in a clamp-like manner and which are held together by springs. The cable or Bowden wire 28 is fixed to one of these friction bushings. In both friction clutches there will be, upon rotation of the shaft and independently of its direction of rotation, a force produced by the frictional resistance, which exerts a pull on the cable or the Bowden wire 28.

What we claim is:

1. A tiltable door mounted in a door frame for swinging movement overhead and comprising rotatably mounted drivable rollers adjacent the upper edge of the door, substantially horizontally extending stationary guide rails in which said rollers are engaged, a compensating

arm on each side of the door, pivotally connected to the door frame portions adjacent the respective sides of the door, one end of each compensating arm being hingedly connected adjacent the lower edge of the door, tension spring means fixed to said door frame and acting on the other ends of said compensating arms, means for varying the effective length of the lever arm of each compensating arm between its hinged connection to the door and its pivotal connection to the door frame, at the door panel ends each compensating arm is provided with an elongate slot for a hinge pin connected to the door, wherein each said slot has an adjustable compression spring associated therewith which spring serves in the closed position of the door to vary the effect of the weight of the door.

2. A tiltable door mounted in a door frame for swinging movement overhead and comprising rotatably mounted drivable rollers adjacent the upper edge of the door, substantially horizontally extending stationary guide rails in which said rollers are engaged, a compensating arm on each side of the door, pivotally connected to the door frame portions adjacent the respective sides of the door one end of each compensating arm being hingedly connected adjacent the lower edge of the door, tension spring means fixed to said door frame and acting on the other ends of said compensating arms, and means for varying the effective length of the lever arm of each compensating arm between its hinged connection to the door and its pivotal connection to the door frame, wherein each end of each compensating arm adjacent the door are mounted on a two armed intermediate lever one arm of which is connected to the door while the other arm is engaged by an adjustable spring connected to the compensating arm.

3. A tiltable door mounted in a door frame for swinging movement overhead and comprising rotatably mounted drivable rollers adjacent the upper edge of the door, substantially horizontally extending stationary guide rails in which said rollers are engaged, a compensating arm on each side of the door, pivotally connected to the door frame portions adjacent the respective sides of the door one end of each compensating arm being hingedly connected adjacent the lower edge of the door, tension spring means fixed to said door frame and acting on the other ends of said compensating arms, and means for varying the effective length of the lever arm of each compensating arm between its hinged connection to the door and its pivotal connection to the door frame, wherein each compensating arm, between its hinged connection to the door and its pivotal connection to the frame, is made of two parts provided with guide means which permit limited displacement of said parts relative to one another.

4. A tiltable door according to claim 3 wherein the opposed ends of said two parts each have a projection passing through an opening in a sleeve surrounding said parts, the length of the opening in the direction of movement of the parts being greater than the thickness of the two projections.

5. A tiltable door as claimed in claim 3 wherein the length of said two parts is such that they touch one another when the door is closed.
